UNITED STATES PATENT OFFICE.

WALTER F. KOKEN AND ANTON J. PICHL, OF ST. LOUIS, MISSOURI.

VALVE MECHANISM FOR INTERNAL-COMBUSTION ENGINES.

1,161,223.

Specification of Letters Patent.

Patented Nov. 23, 1915.

Application filed January 19, 1914. Serial No. 812,895.

To all whom it may concern:

Be it known that we, WALTER F. KOKEN and ANTON J. PICHL, citizens of the United States, residing at the city of St. Louis, 5 State of Missouri, have invented certain new and useful Improvements in Valve Mechanisms for Internal-Combustion Engines, of which the following is a specification.

This invention relates to internal combustion engines of the type in which slide valves are employed for controlling the inlet and exhaust of the gases to and from the cylinders.

The main object of our present invention 15 is to provide a multi-cylinder, four-cycle internal combustion engine, in which two reciprocating valve members arranged side by side are employed for controlling the inlet and exhaust of the gases to and from all 20 of the cylinders of the engine.

Another object is to provide an engine of the type described, in which each valve member consists of a flat plate. And still another object is to provide an engine of the 25 construction above described, in which one of the reciprocating valve members controls the inlet ports of certain cylinders and the exhaust ports of the remaining cylinders, and the other valve member controls the 30 exhaust ports and inlet ports, respectively, of the cylinders that are not controlled by the valve member first referred to.

Figure 1 of the drawings is a top plan view of our improved engine partly in section with the top plate removed; Fig. 2 is a longitudinal sectional view on the line 2—2, Fig. 1; and Fig. 3 is a top plan view of the engine, with the cover removed to expose the reciprocating plates or valve members.

40 For the purpose of illustration an engine having four cylinders 1, 2, 3, and 4, is depicted in the drawings, each cylinder having a piston (not shown) adapted to operate therein in the usual manner and, also, having an inlet port 5 and an exhaust port 6 preferably forward in its head, which ports register in vertical alinement with inlet and exhaust passages 7 and 8, respectively, in the cover 9, which is secured to the heads 45 of the cylinders by bolts 10 or other suitable means. The walls of the passages 7 and 8 project upwardly into a water chamber 11 within the cover 9, and the top of this 50 chamber is closed by a plate 12, which is secured to said cover by bolts 13 or other

suitable means. The inlet passages 7 are connected with the branches of the manifold 14, which has the usual connection with the carburetor, and the exhaust passages 8 are connected with the branches of the exhaust pipe 16. The water-jacket 17, which surrounds the cylinders, is communicatively connected with the water chamber 11 in the cover 9 in the usual manner by means of a pipe 18, which is preferably located at one end of the engine to allow the water which enters the water-jacket 17 through the inlet pipe to pass into the water chamber 11, from which it discharges through the outlet pipe.

70 In the engine herein shown communication between the inlet ports 5 and the exhaust ports 6 of the cylinders and their respective inlet passages 7 and exhaust passages 8 in the cover 9 is established in proper 75 sequence by means of plates 23 or valve members, which reciprocate horizontally upon the heads of the cylinder in a groove or valve chamber 24 in the bottom of the cover 9. In the case of a four-cylinder engine as illustrated in the drawings, two 80 plates 23 are employed, the latter being arranged to reciprocate side by side so that one plate reciprocates over the inlet ports 5 of the cylinders 1 and 4 and the exhaust 85 ports 6 of the cylinders 2 and 3 and the other plate reciprocates over the exhaust ports 6 of the cylinders 1 and 4 and the inlet ports 5 of the cylinders 2 and 3, and there being openings 25 in each plate for the 90 purpose of establishing communication between the inlet ports 5 and exhaust ports 6 and their respective inlet passages 7 and exhaust passages 8 at the proper time. Each 95 plate or valve member 23 is provided at one end with a block or enlarged portion 26, which reciprocates in an enlarged portion 27 of the groove 24 and has the inner end of an operating rod or bar 28 secured thereto by any suitable means. The rods 28 are 100 adapted to be connected to some suitable type of operating mechanism, not shown, which reciprocates the valve members backwardly and forwardly when the engine is in operation and thus causes said valve members to control the inlet and exhaust of the 105 gases to and from the cylinders in proper sequence.

We claim:

1. A multi-cylinder, four-cycle internal

combustion engine provided with a valve chamber that is common to all of the cylinders of the engine, the cylinders having ports that communicate with said valve chamber, and two reciprocating elements arranged side by side in said chamber and each being provided with slide valve portions that control the inlet of the gases to certain cylinders and the exhaust of the gases from the remaining cylinders.

2. A multi-cylinder, four-cycle internal combustion engine, each cylinder of which is provided in its head with an inlet port and an exhaust port, and two plate-like valve members arranged side by side over the heads of the cylinders, one of which is provided with openings that are adapted to register with the inlet ports of certain cylinders and the exhaust ports of the remaining cylinders, and the other member having openings that register with the ports in the cylinders that are not controlled by the valve member first mentioned, said valve members reciprocating back and forth when the engine is in operation and operating to

control the inlet and exhaust of the gases to and from the cylinders in proper sequence.

3. A multi-cylinder internal combustion engine, each cylinder of which has an inlet port and an exhaust port formed in its head, a cover having inlet and exhaust passageways that coöperate with the ports in the cylinders and also being provided with a valve chamber that is common to all of the cylinders, and a pair of positively-operated reciprocating valve members arranged side by side in said valve chamber, and each of which is provided with means for controlling the inlet of the gases to certain cylinders and the exhaust from the remaining cylinders.

In testimony whereof we hereunto affix our signatures in the presence of two witnesses.

WALTER F. KOKEN.
ANTON J. PICHL.
